FOUNTAIN PEN

Carl J. Cardin, Downers Grove, Ill.

Application November 29, 1944, Serial No. 565,584

14 Claims. (Cl. 120—42.01)

1

The present invention relates to fountain pens and the like, and more particularly to a fountain pen cap arranged to provide a positive joint between cap and barrel with the resulting pressure between these members always being the same; not depending upon friction to maintain this joint and further to provide quicker application and removal than heretofore.

In general fountain pens are provided with screw caps having at the interior a sealing cap portion adapted to engage the end of the fountain pen barrel. If the cap is not tightly screwed upon the barrel, the seal is imperfect resulting in accumulation of ink at the end of the barrel at the point near the pen point where the pen is to be held by the fingers. Such caps are usually retained during the use of the pen at the other end of the barrel by frictional engagement. In order to provide adequate strength to prevent breakage of the barrel by this frictional engagement, it is customary to provide one or more metal rings about the cap. The most annoying disadvantage of a screw or friction joint is that the cap and barrel become disengaged while being carried because they are only held together by friction. The pen point then comes in contact with the clothing causing an ink spot. If the pen is carried on a cord or chain the barrel often becomes disengaged from the cap and is lost.

In order to overcome some of these objections, it has been proposed to provide a cap for a fountain pen barrel which is retained in position by latching or locking means. In the past such attempted constructions have not found commercial favor because of various disadvantages either in use or in the cost of manufacture. In accordance with the present invention the above mentioned and other disadvantages are overcome by providing a fountain pen cap which is latched or locked into position at either end of the pen so that a positive disengaging action must be used to release the cap from its position at the end of the pen barrel.

It, therefore, is an object of the present invention to provide an improved fountain pen structure having a cap that can be disengaged from the barrel only by positive manual action.

It is another object of the present invention to provide an improved fountain pen structure whereby the cap may be engaged with or disengaged from the pen barrel more rapidly than in prior constructions.

Still another object of the present invention is to provide in conjunction with this cap an improved pocket clip arrangement for retaining the

2

pen in position on the clothing to which it is attached.

Still another object of the present invention is to provide an improved fountain pen structure having a positive locking action between the barrel and cap so that the pen may be carried by a chain or cord attached to the top of the cap or may be carried in a purse or bag without fear of disengagement of the cap from the barrel.

10 Still another object of the present invention is to provide an improved fountain pen cap structure which will have a predetermined degree of sealing action upon application of the cap to the pen for closing.

15 Other and further objects of the present invention subsequently will become apparent by reference to the following description taken in connection with the accompanying drawing wherein

Figure 1 shows, principally in cross section, a 20 fountain pen barrel and cap constructed in accordance with the present invention;

Figure 2 is a cross sectional view in the direction of the arrows along the line 2—2 of Figure 1;

Figure 3 is a cross sectional view in the direction of the arrows along the line 3—3 of Figure 1;

Figure 4 is an exploded positive view of the elements comprising the cap embodied in the present invention;

Figure 5 is a cross sectional view of the upper 30 portion of the invention as seen in Figure 1 illustrating the initial unlocking action;

Figure 6 is a view similar to Figure 5 illustrating a subsequent action which permits removal of the cap from the fountain pen barrel;

35 Figure 7 is a view illustrating the gripping action of the pocket clip construction in conjunction with the locking clip;

Figures 8 and 9 show certain modifications of a portion of the fountain pen barrel;

40 Figure 10 shows a modified form of cap adapted for use with a fountain pen and barrel such as shown in Figure 1;

Figure 11 is a cross sectional view as seen in the direction of the arrows along the line 11—11 45 of Figure 10;

Figures 12, 13, 14, and 15 each show different fountain pen cap structures embodying the present invention; and

Figure 16 is a cross sectional view as seen in 50 the direction of the arrows along the line 16—16 of Figure 15.

In Figure 1 of the drawing there is shown a fountain pen barrel 20 of a structure of any desired type suitable for fountain pens. Since the 55 particular type of barrel structure in general

forms no part of the present invention, only such portions as are pertinent to the present invention have been shown in cross section. At the upper end of the barrel 20 a threaded portion 22 is provided for receiving a threaded end of a pen and feed carrying member 24. A suitable pen point 26 and pen feed member 28 of any desired type of construction is mounted in the pen supporting or holder portion 24. The portion 24 has a tapered surface 30 which is adapted to be engaged by the inner sealing cap portion of the outer cap as subsequently will become apparent. The member 24 is provided with an annular undercut portion 32 so as to form with the end of the barrel 20 an annular undercut recess adapted to be engaged by latching or locking members supported by the fountain pen cap.

A fountain pen cap having a tubular portion 34 and an upper end portion 36 is arranged to extend over the end of the fountain pen barrel for a distance beyond the annular recess 32. The end portion 36 is secured to the tubular portion 34 by a suitable threaded arrangement 38, and interposed between the inner end of the tubular portion 34 and the end member 36 are a pocket clip 40 and a resilient spring latching member 42. In the proximity of the annular undercut recess 32 the cap portion 34 is provided with an aperture 44 so that the inversely curved end or hook portion 46 of the spring latching and locking member 42 may extend inwardly into the interior of the cap and into engagement with the undercut portion of the annular recess 32 in the barrel 20. The end member 36 of the fountain pen cap is provided with a cavity 48 partially closed by a plug 50 threadedly mounted therein. The plug 50 is provided with a circular opening 52 and an inner connecting recess 54 best shown in Figures 2 and 4. The recess 54 is provided so that the solid cylindrical portion 56 of an inner cap sealing member may be inserted in position. The sealing member adjacent the top of the cylindrical portion 56 is provided with a cap portion 58 and at the other end the cylindrical portion is provided with an enlarged diameter portion 60 connected to a still larger diameter portion 62. The portions 60 and 62 are provided with a coaxial cavity 64 to accommodate the pen point and pen feed. A suitable spring 66 is interposed between the plug member 50 and the shoulder formed between the two portions 60 and 62 of the inner cap. The bottom edge of the inner cap portion 62 preferably is bevelled slightly as at 68 so as to engage the tapered portion 30 of the pen supporting member 24 of the fountain pen barrel to provide a line contact seal and to provide a more gentle entrance of the pen point into the cavity 64 therefore diminishing chance of injury to the pen point while engaging the cap and barrel.

From the upper portion of Figure 1 it will be seen that the latching member 46 is in engagement with the annular groove 32 so as to retain in position the cap of the pen relative to the barrel. In order to support the cap at the other end of the barrel during normal use of the fountain pen, the barrel 20 may be provided with an end member 70 supported by a threaded portion 72 with respect to the end of the barrel 20 so that an annular recess 74 having an undercut portion is provided for the same purpose as the annular recess 32 at the other end of the fountain pen barrel.

In order to disengage the fountain pen cap comprising the tubular member 34, and the end

portion 36 from the fountain pen barrel 20, the fountain pen barrel is moved upwardly in the tubular section 34 so as to partially compress the spring 66 thus moving the top end 58 of the inner seal cap further up into the cavity 48. This action moves the lip of the undercut recess 32 up sufficiently so as to be disengaged from the reversely formed end portion 46 of the latching and retaining spring member 42. In order to move the end portion 46 of the latching spring member 42 outwardly away from the recess 32 of the fountain pen barrel 20 pressure is applied to the pocket clip 40 in the direction of the arrow shown in Figure 6 so as to bring about an outward movement of the end 46 of the spring latching member 42. It will be noted that in Figure 1 the spring member 42 is provided with bent portions 76 and 78 providing an intermediate offset portion in the proximity of the ball end 80 of the fountain pen pocket clip 40. Pressure applied upon the pocket clip 40 causes the ball end to move toward the cap 34 so as to bring about a flexure of the intermediate portion of the spring member 42 with the portion 76 providing a fulcrum bearing against the cap. This action forces the hook end 46 to shift about the fulcrum outwardly from engagement with the recess 32 of the fountain pen barrel 20 so that the pen may be withdrawn from its cap. After withdrawal from the cap, the other end of the fountain pen may be inserted in the cap so that the latching member 46 will engage the recessed undercut groove 74 at the other end of the pen thus providing a fountain pen assembly having the proper balance and feel for writing, and the cap is positively attached to the barrel while the pen is being used.

Since the pocket clip 40 is placed in alignment with the spring latching member 42 so that during disengagement of the cap with the end of the barrel the pocket clip 40 operates to flex the latching member 42, further cooperation is obtained between the pocket clip and the spring member 42 to provide improved clamping or gripping action of the pocket clip 40 with the fabric 82 of a pocket so as to prevent accidental displacement of the fountain pen. This structure and operation are illustrated by Figure 7 which shows the upper end of the fabric 82 engaged by a wedge shaped area between the pocket clip 40 and the spring locking member 42.

While the undercut annular recessed grooves 32 and 74 of the pen structure shown in Figure 1 have been made by integrally forming the lip from the adjoining material, other manners of construction may be employed. In Figure 8 the upper portion 24 adjoining the fountain pen barrel 20 is provided with a recess 33. A metal ring 84 is supported from an undercut portion 60 of the member 24 so as to form the lip which is to be engaged by the reversely bent end portion 46 of the locking spring 42. Still another form of construction is illustrated in Figure 9 wherein an annular groove 31 is formed, and two rings 86 and 88 are provided to form an undercut recess 35. The rings 86 and 88, particularly for the smaller size pen barrels, have the advantage of providing greater strength and resistance to the wearing action of the hook portion 46 of the spring locking member 42 than is the case where the recess is formed by shaping the material from which the body of the pen is made.

Figures 10 and 11 show a fountain pen cap of a modified form wherein the main body portion 90 is formed with a large annular cavity 92 and

a smaller cavity 94. The larger cavity 92 accommodates the outer diameter of the pen barrel, and the smaller cavity 94 accommodates the pen point and pen feed portions of the fountain pen. It will be noted that these two coaxial cavities are interconnected by a bevelled portion 96 so as to provide the line point contact seal and a more gentle entrance of the pen point into the small cavity heretofore described in connection with the embodiment in Figure 1. The upper end of the cap body 98 is provided with a cavity 98 having a threaded portion 100 for receiving a plug 102 having a central aperture therein. The central aperture accommodates a plug member 104 having a cap portion 106 arranged adjacent the bottom of the supporting plug 102. The inner plug 104 extends above the top of the outer plug 102. The cap portion 106 of the plug 104 is adapted to engage a locking spring member 108 having a reversely turned or hooked portion 110 for engagement with the grooves 32 and 74 of the fountain pen barrel shown in Figure 1. The spring locking member 108 is suitably apertured so that it may be fastened in position by a cap screw 112 as is apparent from Figures 10 and 11. A pocket clip 40 is supported between the upper end of the barrel body 90 and the plug 102. Immediately adjacent the ball terminal 80 of the pocket clip 40, the spring locking member 108 is provided with bent portions 114 and 116 providing the offset portion and fulcrum and so arranged that when pressure is applied on the ball 80 together with the pressure exerted upon the plug 104, a downward and outward movement of the hook end 110 will be obtained.

Figure 12 shows another form of pen cap having a tubular barrel portion 118 provided with a plug 120 for securing in position the pocket clip 40 and the locking spring 42. A movable sealing ring 122 is connected to a Sylphon bellows structure 124 which is attached to the bottom of the plug 120. The bellows structure 124 therefore constitutes a resilient member urging the inner sealing cap 122 against the end of the pen barrel. The inner portion of the bellows 124 also serves to receive the end of the fountain pen in a manner similar to the cavity 64 shown in Figure 1. In order to release the cap shown in Figure 12 the same manual manipulations must be employed as described in the embodiment shown in Figure 1.

Figure 13 shows another embodiment in which the parts have been given reference characters corresponding to similar parts shown in Figure 12. The cylindrical barrel portion 118 is provided with an end plug 121 having a depending portion 126 to which is secured a tube 128 of resilient material such as rubber. The other end of the resilient or rubber tube 128 is connected to a tubular sealing member 130. The space within the resilient cylindrical member 128 accommodates the pen point and pen feed. The resilient member 128 urges the member 130 against the end of the pen barrel to provide the proper sealing action. To engage and disengage the cap shown in Figure 13 to or from the fountain pen barrel requires the same manual manipulations heretofore described in connection with Figure 1.

In Figure 14 there is shown a fountain pen cap having a cylindrical tubular portion 132 provided with an end cap portion 134. Mounted within the tubular portion 132 is a sealing cap member 136 resiliently biased outwardly by a spring 138. The upper portion of the inner sealing cap 136 is of lesser diameter than the lower portion and is

arranged to move within a recess 140 in the upper cap member 134. The upper cap member 134 is provided with two coaxial bores 142 and 144. A movable member comprising a cylindrical body 146 fitting within the bore 142 has a head portion 148 which fits within the recess 144 of the cap portion 134. The head portion 148 of the cylindrical body 146 is of lesser height than the depth of the recess 144 so that the position of the cap 148 will be indicative of the position of the recess 32 of the fountain pen barrel within the fountain pen cap. In order to disengage the fountain pen barrel and its recess 32 from the spring locking hook 46 the fountain pen barrel is moved upwardly against the action of the resilient spring 138 so that the cap member 148 is above the upper end of the member 134 thereby indicating that the undercut portion of the annular groove 32 has been disengaged from the upper end of the hook 46 of the locking spring 42. Thereafter pressure may be applied to the pocket clip 40 in the manner previously described in connection with the operation of the embodiment in Figure 1 to cause the hook portion 46 to be moved outwardly from complete engagement with the groove 32 in the member 24 at the end of the fountain pen barrel 20.

The structure shown in Figure 14 operates to prevent a displacement of the cap relative to the barrel sufficient to move the locking spring and the end of the hook 46 thereof to a position where the locking spring could be removed from the annular groove 32 on the barrel 20. Thus if the pen is being carried in the pocket and due to a bending or crouching action on the part of the wearer, pressure is applied to the top of the barrel to produce partial axial displacement, further movement of the barrel will be prevented when the top 148 of the plug or cylindrical body 146 is engaged by the wearer's body. Thus when the top 148 is flush with the cavity 144 in the cap of the pen, further axial movement of the cap relative to the pen barrel is prevented and even if at any time pressure is also applied to the pen clip 40, no unlatching or unlocking action can be brought about. Thus there is absolute security of a locking action between the cap and the fountain pen barrel under these conditions.

A still further fountain pen cap structure is shown in Figures 15 and 16 wherein the cap has a cylindrical tubular portion 150 closed at the top by a plug portion 152. Within the tubular portion 150 is a slidable sealing cap member 154 resiliently biased outwardly by a spring 156. The lower end of the plug portion 152 is provided with a threaded portion 158 which engages the internally threaded upper end of the tubular member 150. Suitable apertures 160 are provided at opposite sides of the threaded portion 158 for receiving a resilient spring member 162 best seen in Figure 16. The upper end of the sealing cap 154 has a reduced diameter portion 164 provided with a head portion 166. The ends of the spring 162 are arranged to extend beneath the head 166 so as to limit the outward action of the resilient spring 156 against the lower shoulder of the sealing cap 154. This manner of construction facilitates rapid and economical assembly of a cap of this type. The operations required to disengage the latching hook 46 from the undercut annular groove in the fountain pen barrel are similar to the action heretofore described in connection with Figure 1.

While for the purpose of illustrating and describing the present invention, certain preferred

embodiments have been shown in the drawings, it is to be understood that certain modifications and variations may be made. In the drawing the pocket clip 40 and the resilient retaining spring 42 have been shown as being made of two pieces of metal, and obviously a unitary metal construction may be employed. Alternatively the members 40 and 42 may be provided with interlocking members so as to preclude relative rotation if the securing cap 36 should become slightly loosened. Other variations in the arrangements of the parts and their configurations are intended as may be commensurate with the spirit and scope of the invention defined in the appended claims.

This invention is hereby claimed as follows:

1. The combination comprising a fountain pen barrel having an undercut annular groove, an external cap adapted to be fitted over the end of said pen and to extend beyond said groove, said cap being provided with an aperture in the proximity of said groove when said cap is fitted over said barrel, a sealing cap slidably mounted within said external cap for engagement with the end of said pen barrel, resilient means mounted within said cap for urging said sealing cap against the end of said barrel, a connecting member to unite said external cap and said sealing member comprising a shaft and headed portion, said shaft operably connected to said sealing cap with said headed portion positioned externally of said cap, and an elongated spring catch carried by said external cap and having an end portion adapted to extend through said aperture for engagement with said groove.

2. The combination comprising a fountain pen barrel having an undercut annular groove, an external cap adapted to be fitted over the end of said pen and to extend beyond said groove, said cap being provided with an aperture in the proximity of said groove when said cap is fitted over said barrel, a sealing cap slidably mounted within said external cap for engagement with the end of said pen barrel, resilient means mounted within said cap for urging said sealing cap against the end of said barrel, an axial recess at the end of said external cap, said recess being provided with an axial aperture, a cylindrical member positioned in said recess through said aperture and secured to the end of said sealing cap, said cylindrical member having an enlarged portion positioned within said recess of said external cap to limit axial displacement of said external cap relative to said barrel by the application of force on the end of said external cap, and an elongated spring catch carried by said external cap having an end portion adapted to extend through said first mentioned aperture for engaging with the groove of said pen barrel.

3. A closure for a cylindrical member comprising a tubular member closed at one end and adapted to fit over said cylindrical member, said cylindrical member having recessed locking means and said closure having an aperture in the proximity of said locking means when the said closure is fitted over said cylindrical member, an elongated spring member with one end thereof mounted adjacent the closed end of said closure and with the free end thereof reversely turned inwardly and positioned to extend through said aperture and into engagement with said locking means and having at least a portion intermediate the ends thereof bent outwardly and normally spaced from the adjacent surface of said closure whereby to maintain said reversely

turned end in engagement with said groove, and said outwardly bent portion being shiftable inwardly toward the surface of said closure with an adjacent part of said spring member in engagement therewith to provide a fulcrum for effecting movement of said reversely turned end out of engagement with said locking means as the effective length of said spring member is increased.

4. A cap for a fountain pen barrel comprising a tubular member closed at one end and adapted to fit over said barrel, said fountain pen barrel having an undercut locking shoulder, said cap having an aperture in the proximity of said shoulder when the cap is fitted over said barrel, an elongated spring latching member mounted at the closed end of said cap and having a reversely turned end portion positioned to extend through the aperture in said cap for interlocking engagement with said shoulder and including an intermediate offset portion normally spaced outwardly from the adjacent surface of said cap whereby to maintain the said reversely turned end portion in engagement with said shoulder, said offset portion being shiftable inwardly with the lower end thereof in contact with said cap to provide a fulcrum whereby said reversely turned end portion will shift outwardly about said fulcrum and out of interlocking engagement with said shoulder as the effective length of said latching member is increased.

5. A cap for a fountain pen barrel comprising a tubular member closed at one end and adapted to fit over said barrel, said fountain pen barrel having an undercut groove, said cap having an aperture in the proximity of said groove when the cap is fitted over said barrel, an elongated spring latching member mounted at the closed end of said cap and having a reversely turned end portion positioned to extend through the aperture in said cap for engagement with said groove, said spring latching member having an intermediate portion thereof in contact with said cap to provide a fulcrum and including an offset portion immediately above said fulcrum and normally spaced outwardly from the adjacent surface of said cap whereby to maintain the reversely turned end portion in engagement with said groove, and means engageable with said offset portion to shift the same inwardly toward the adjacent surface of said cap whereby to increase the effective length of said spring latching member and to cause outward movement of said reversely turned end portion about said fulcrum and out of engagement with said groove.

6. A cap for a fountain pen barrel comprising a closed tubular member adapted to fit thereover, said fountain pen barrel having an undercut annular groove, said cap having an aperture adapted to register with said groove when said cap is fitted over said barrel, an elongated spring latching member mounted on said cap and having a reversely turned end portion positioned so as to extend through said aperture for engagement with said groove, said latching member being normally spaced outwardly from said cap and including an inwardly bent portion intermediate the ends thereof providing a fulcrum when in engagement with said cap, an internal slideable sealing cap adapted to seat against the end of said barrel, coiled spring means resiliently biasing said internal sealing cap toward said barrel, means for causing said spring latching member to be moved axially relative to said barrel to disengage said end portion from the undercut por-

tion of said groove, and means cooperating with said latching member above said fulcrum and operable upon inward movement to shift said end portion outwardly about said fulcrum toward the exterior of said cap.

7. The combination comprising a fountain pen barrel having an annular locking member, an external cap adapted to be fitted over the end of said pen barrel and said locking member, a sealing cap slidably mounted within said external cap for engagement with the end of said pen barrel, resilient means mounted within said external cap for urging said internal cap against the end of said barrel, an elongated spring catch carried by said external cap and having an end portion adapted to engage said locking member, said spring catch having an outwardly offset portion intermediate the ends thereof with a part thereof immediately below said offset portion providing a fulcrum when in engagement with said cap, and a pocket clip mounted on said external cap with the end thereof adjacent said offset portion and operable thereagainst to flex said offset portion inwardly whereby to displace the end portion thereof longitudinally of said barrel and transversely about said fulcrum upon relative axial movement of said spring catch relative to the barrel.

8. The combination comprising a fountain pen barrel having an undercut annular groove, a cap adapted to be fitted over the end of said pen and to extend beyond said groove, said cap having an aperture adapted to be placed in register with said groove, a sealing member slidably mounted within said cap for engagement with the end of said pen barrel, a resilient tubular member supporting said sealing member within said cap and biasing said member toward the end of said pen barrel, an elongated spring latching member mounted on said cap and having a reversely turned end portion positioned so as to extend through said aperture for engagement with said groove, said latching member having an outwardly offset portion intermediate the ends thereof with a part thereof immediately below said offset portion providing a fulcrum when in engagement with said cap, and a pocket clip mounted in alignment with said elongated spring latching member with a portion thereof adapted to engage said offset portion for shifting the same inwardly to cause the end of said spring latching member to shift outwardly about said fulcrum and to be disengaged from said groove.

9. A cap for a fountain pen barrel comprising a tubular member closed at one end and adapted to fit over said barrel, said fountain pen barrel having an annular groove with an overhanging lip, said cap having an aperture in the proximity of said groove when said cap is fitted over said barrel, an elongated spring latching member on said cap and having a reversely turned end portion positioned so as to extend through said aperture for engagement with the overhanging lip of said annular groove, the lower portion of said spring latching member normally lying adjacent the outer surface of said cap to provide a fulcrum and with a portion thereabove bent outwardly, a pocket clip mounted on said cap in alignment with said spring latching member and with the end thereof adjacent said outwardly bent portion, and means mounted adjacent the top of said cap for moving said elongated spring latching member downwardly to a position whereby action of said pocket clip against said outwardly bent portion

will cause the end of said spring member to move about said fulcrum outwardly from said cap.

10. A cap for a fountain pen barrel comprising a closed tube member adapted to fit over said barrel, said fountain pen barrel having an undercut annular groove, said cap having an aperture in the proximity of said groove when said cap is fitted over said barrel, an elongated spring latching member mounted on said cap and having a reversely turned end portion positioned so as to extend through the aperture in said cap for engagement with the undercut portion of said annular groove, said spring latching member having a fulcrum portion lying adjacent said barrel adjacent the reversely turned end and an outwardly offset portion thereabove, and a pocket clip mounted in alignment with and overlying said spring latching member for selective cooperation with said offset portion in response to radial pressure applied to said clip to flex said offset portion inwardly whereby to cause the end of said spring latching member to be moved about said fulcrum and outwardly from said aperture.

11. A cap for a fountain pen barrel comprising a closed tubular member adapted to fit thereover, said fountain pen barrel having an undercut annular groove, said cap having an aperture adapted to register with said groove when said cap is fitted over said barrel, an elongated spring latching member mounted on said cap and having a reversely turned end portion positioned so as to extend through said aperture for engagement with said groove, an internal sealing cap adapted to seat against the end of said barrel, coiled spring means resiliently biasing said internal sealing cap toward said barrel, said latching member having an outwardly bent portion above the end portion thereof and normally spaced outwardly from said cap, for causing said spring latching member to be flexed automatically to engage said end portion in said groove, and means operable against the outwardly spaced portion of said latching member for causing said latching member to fulcrum against said cap and to be flexed inwardly whereby to disengage said end portion from said undercut annular groove and to move said end about the fulcrum toward the exterior of said cap.

12. The combination comprising a fountain pen barrel having an undercut annular groove, a cap adapted to be fitted over the end of said barrel and to extend beyond said groove, said cap having an aperture adapted to be placed in register with said groove, an elongated spring latching member mounted on said cap and having a reversely turned end portion positioned so as to extend through said aperture for engagement with the groove of said barrel, a sealing member slidably mounted within said cap for engagement with the end of said barrel, a resilient bellows member between said cap and said sealing member to bias said sealing member against the end of said pen barrel, said spring latching member having a fulcrum portion lying adjacent said barrel adjacent the reversely turned end and an outwardly offset portion thereabove, and a pocket clip mounted in alignment with and overlying said spring latching member for selective cooperation with said offset portion in response to radial pressure applied to said clip to flex said offset portion inwardly whereby to cause the end of said spring latching member to be moved about said fulcrum and outwardly from said aperture.

13. The combination comprising a fountain pen barrel having an annular recess with an over-

hanging lip, an external cap adapted to be fitted over the end of said barrel and to extend beyond said recess, said cap having an aperture therein in the proximity of said recess, a sealing member slidably mounted within said external cap for engagement with the end of said pen barrel, resilient means mounted within said cap for urging said sealing member against the end of said barrel, an elongated spring latching member mounted on said cap and having a reversely turned end portion arranged to extend through said cap aperture for engagement with the lip of said annular recess, said spring latching member having adjacent its lower portion a fulcrum engageable with the surface of said cap and having adjacent its upper portion an outward offset portion spaced away from the surface of said cap, and a pocket clip mounted on said cap to overlie the offset portion of said spring latching member cooperating therewith to engage the fabric adjacent the pocket of a garment by a wedging action, said pocket clip being adapted when pressed inwardly against said spring latching member to cause inward flexing thereof and outward movement of the end portion about said fulcrum to displace the reversely turned end portion from said recess.

14. A cap for a fountain pen barrel comprising a closed tubular member adapted to fit over said barrel, said fountain pen barrel having an undercut annular groove, said cap having an aperture in the proximity of said groove when said cap is fitted over said barrel, an elongated spring latching member mounted on said cap and having a reversely turned end portion positioned so as to

extend through the aperture of said cap for engagement with the undercut portion of said annular groove, said latching member having an intermediate portion adapted to engage said cap and provide a fulcrum thereagainst and an outwardly bent portion above said fulcrum spaced outwardly from said cap, and a pocket clip mounted on said cap in alignment with said elongated spring latching member with the free end thereof of adjacent said outwardly bent portion and adapted upon inward movement thereof to cause said outwardly bent portion to be flexed inwardly and to move the reversely turned end portion of the latching member outwardly about said fulcrum as said end portion and said pen barrel are moved axially relative to each other.
